UNITED STATES PATENT OFFICE.

WILLIAM V. R. SELTZER, OF EPHRATA, PENNSYLVANIA.

LAMP-SHADE HOLDER.

933,125.

Specification of Letters Patent. Patented Sept. 7, 1909.

Application filed April 15, 1907. Serial No. 368,422.

To all whom it may concern:

Be it known that I, WILLIAM V. R. SELTZER, citizen of the United States, residing at Ephrata, in the county of Lancaster and 5 State of Pennsylvania, have invented certain new and useful Improvements in Lamp-Shade Holders, of which the following is a specification.

This invention relates to improvements in 10 lamp shade holders and the device herein shown and described is intended more particularly for use on a depending electric lamp.

The invention consists of means for securing 15 the shade in the holder without the use of screws or other adjusting devices and consists of means for securely holding the shade while still permitting its easy and rapid withdrawal.

20 The invention is more fully described in the specification following, and clearly illustrated in the accompanying drawing, in which:—

Figure 1 is a plan view of my holder. 25 Fig. 2 is a sectional view taken through line X—X of Fig. 1.

The device comprises a body having an annular ring or wall 1 at its periphery and with the usual socket holding clamp 2. The 30 wall or ring 1 is formed with a series of retainers 3, formed integral therewith; the entire device being formed of spring sheet metal. In the drawing I have shown the device provided with three of these retainers. 35 These retainers, with the exception of one of them represented by 3^a, are bent inwardly, at right angles to the wall 1, flush with the top thereof, and then downwardly and against the inside of said wall, forming 40 approximately a triangle in cross-section and making a semi-rigid retainer.

The excepted retainer 3^a, referred to above, is in the form of a spring clip or snap device. This retainer is also formed 45 integral with the ring and is bent inwardly from the base of said wall at an angle of

approximately 45 degrees to a point on horizontal alinement with the upper edge of said wall. From this point it is curved outwardly and upwardly to form an approximate semi-circle, letting its extremity come outside of the peripheral line of the body. 50

When it is desired to secure a shade in the holder, the rib of the shade is entered in the holder under the projecting ends of the retainers 3 and a slight pressure will cause the clip 3^a to bend outward and allow the shade to be seated in the holder, while at the same time it will securely hold it against accidental removal but will permit its easy 55 intentional removal.

It is evident that inasmuch as there are no screws or other adjusting devices to be operated, the placing and removal of the shade is easily accomplished. It is also 60 evident that the device may be used in gas lamps, chandeliers or other places where a shade is to be supported in either upright or inverted position and also that its construction is such as to adapt it to shades of 65 usual or ordinary construction.

Having thus fully described my invention and its operation, what I claim and desire to secure by Letters Patent is:—

A lamp shade holder formed from one 70 piece of metal comprising a disk-shaped base, a non-yielding vertical peripheral flange formed integral with said disk, a resilient finger projecting from said disk, and semi-rigid complementary fingers integral 75 with said flange, each of said semi-rigid fingers comprising an inwardly extending portion and a rearwardly and downwardly extending portion adapted to be braced 80 against said flange upon the application of 85 pressure.

In testimony whereof I affix my signature, in presence of two witnesses.

WILLIAM V. R. SELTZER.
